LOUVERED FLUORESCENT LIGHTING
FIXTURE

Carl X. Meyer, St. Louis, and James F. Whitehead,
Jr., Kirkwood, Mo., assignors to Day-Brite
Lighting, Inc., St. Louis, Mo., a corporation of
Missouri

Application September 1, 1949, Serial No. 4,805

Term of patent 14 years

(Cl. D48—23)

To all whom it may concern:

Be it known that we, Carl X. Meyer and James F. Whitehead, Jr., citizens of the United States and a resident of the city of St. Louis, State of Missouri, and the city of Kirkwood, in the county of St. Louis, and State of Missouri, respectively, have invented a new, original, and ornamental Design for Louvered Fluorescent Lighting Fixture, of which the following is a specification, reference being had to the accompanying drawing, forming part thereof.

Fig. 1 is a bottom perspective view of a louvered fluorescent lighting fixture, showing my new design.

Fig. 2 is a top plan view of the fixture.

Fig. 3 is an elevational view of the side opposite to that shown in Fig. 1.

Fig. 4 is an enlarged elevational view of the end opposite that shown in Fig. 1; and

Fig. 5 is an enlarged vertical cross-sectional view on the line 5—5 in Fig. 3.

We claim:

The ornamental design for a louvered fluorescent lighting fixture, substantially as shown.

CARL X. MEYER.

JAMES F. WHITEHEAD, JR.
